MEANS FOR PRODUCING AN INCANDESCENT IMAGE

Philo T. Farnsworth, Springfield Township, Montgomery County, and Bernard C. Gardner, Philadelphia, Pa., assignors, by mesne assignments, to Farnsworth Television & Radio Corporation, Dover, Del., a corporation of Delaware

Original application May 6, 1936, Serial No. 78,188.
Divided and this application September 20, 1937,
Serial No. 164,624

3 Claims. (Cl. 250—164)

This invention relates to a method of producing an incandescent image for use as a primary light source in the projection of images, such as oscillographic traces, television images, or the like.

This application is a division of our prior application entitled "Luminescent screen", Serial No. 78,188, filed May 6, 1936, since matured into U. S. Patent No. 2,098,000, issued November 2, 1937, which is a substitute for original application also entitled "Luminescent screen", Serial No. 614,501, filed May 31, 1932. The prior application referred to disclosed and claimed an apparatus, whereas the present application is directed solely to a method of operation whereby an incandescent image can be produced within a cathode ray tube.

Among the objects of our invention are: To produce an incandescent image; to produce such an image having sufficient brilliance that it may be used as a primary light source for projection; to provide a method of producing an incandescent image suitable for projection; and to provide a single and efficient method of creating an incandescent image in a cathode ray tube, which can be utilized as a primary light source in the focus of a projection lens without substantial image distortion, keystoneing, or angular relationships.

Our invention possesses numerous other objects and features of advantage, some of which, together with the foregoing, will be set forth in the following description of specific apparatus embodying and utilizing our novel method. It is therefore to be understood that our method is applicable to other apparatus, and that we do not limit ourselves, in any way, to the apparatus of the present application, as we may adopt various other apparatus embodiments, utilizing the method, within the scope of the appended claims.

As examples of other apparatus which can be utilized to practice our method, reference may be had, for example, to United States Patent No. 2,066,070, issued December 29, 1936, to Philo T. Farnsworth and Harry S. Bamford on an "Incandescent light source", or to the copending Farnsworth application entitled "Luminescent screen and method of use", Serial No. 655,784, filed February 8, 1933.

Referring to the drawing:

Fig. 1 is a longitudinal sectional view through an oscillograph or television receiver tube embodying this invention.

Fig. 2 is a sectional view on a larger scale through the luminescent screen shown in Fig. 1.

Figs. 3 and 4 are sectional views illustrating modified forms of the screen of our invention.

Fig. 5 is a diagram showing our invention used as a light source for picture projection.

For many years it has been customary to form the luminescent screen used in cathode ray oscillographs and the like, of materials which fluoresce under the bombardment of the rays, such as calcium tungstate or barium platinum cyanide, with or without an admixture of a phosphorescent material such as zinc sulphide. Luminescent screens of this character have the advantage of very great luminous efficiencies with low input power. Where the electron stream carries relatively low current and travels with moderate velocity, its trace on the screen is clearly visible under conditions of moderate external illumination. If, however, the attempt is made to increase the illumination beyond a certain very moderate limit, only slight increases are obtained even with very great increases in the input power, and there is a strong tendency for the material of the screen to break down and become inactive under the bombardment. Moreover, the light from the screen is usually very definitely colored, usually having a bluish or greenish tinge which makes it undesirable for television use, where a definite esthetic effect is aimed at. The purpose of this invention is to provide a screen which shows the trace of the cathode ray beam in pure white light, and which is capable of almost indefinite increases in the amount of power which it transforms into visible radiation. Although the method here employed is less sensitive on small power inputs than is the fluorescent screen, we have found that with large power inputs the efficiency may approach that of the conventional screen, giving an output power vastly greater than is possible with conventional methods.

Considered from the aspect of the apparatus employed, our invention comprises the combination with a source of cathode rays of a screen having a surface of refractory material which is capable of being raised to incandescence by the impact of the rays, this material being so disposed as to prevent material thermal conduction to adjacent portions of the surface, i. e., so disposed that the heat loss from an incandescent surface element by radiation is greater than its loss by conduction to adjacent surface elements. These requirements of the screen are met in sufficient degree to be operative by a sufficiently thin sheet of refractory metal of low thermal conductivity, such as a sheet of molybdenum foil, but the luminous efficiency in this case is low.

- The preferred type of screen is formed by impregnating a pile fabric, such as a finely woven short pile rayon velvet, with salts of a metal or metals whose oxides are poor emitters of infrared or heat rays, and then oxidizing the screen, burning out the fabric, and converting the salts to the oxides. Salts of calcium, magnesium, thorium, cerium, zirconium and uranium are examples of the class of materials used to impregnate the fabric, the preferred combination being a mixture of thorium with a small amount of uranium. Screens of this type, bombarded from the pile side and preferably viewed from the same side, are capable of radiating at a rate of about two candle power per watt input. Screens based on pileless fabrics lie intermediate the velvet base and the metal foil screens in sensitivity and speed of response.
- Considered from the point of view of the method involved, the invention comprises, broadly, the steps of generating a pencil or beam of cathode rays, directing the rays against a screen of refractory material so as to raise the point of impact to incandescence, and deflecting the beam so that it impinges upon successive elementary areas of the screen, while preventing material transfer of heat between the incandescent elements and adjacent elements.
- The form of the invention illustrated in the drawing comprises the usual evacuated envelope having at one end a reentrant stem 2, which carries an electron gun. The cathode (not shown) is heated by current supplied through leads 4 and 5, emitting electrons which are attracted by the conical projection 6 on a circular anode 7, and pass through a beam canal in the anode to form the required beam of cathode rays. A pair of supports 9 connect the anode to longitudinal struts 10, preferably of curved cross section, which extend almost the full length of the tube and which are welded or otherwise secured at their lower ends to a clamp ring 11, surrounding the stem 2. A lead wire 12 connects to one of the anode supports and is brought out through a separate side seal 14, to permit the necessary positive potential to be supplied to the anode. The intensity of the beam is regulated by a control electrode or grid 15, mounted on a lead 16 sealed through the stem.
- The longitudinal support rods 10 carry, at their upper or distal ends, a ring 17 which supports the luminescent screen 19. The ring 17 is of U-shaped cross section, the arms of the U being crimped to hold the fabric 20 upon which the screen is formed. This is preferably a cut rayon velvet of very fine weave and short pile, the general rule being the finer the weave the more satisfactory the screen. The fabric is mounted with the pile 21 toward the electron gun. It is impregnated with a mixture of salts whose oxides form the light emitters or radiators of the completed screen. These materials are preferably a mixture whose basic radicals comprise approximately 99 per cent thorium and 1 per cent uranium. To this may be added a small proportion of aluminum and/or beryllium salt. In general, the salts used are nitrates, because of their high degree of solubility and the ease with which they are converted into the oxide.
- The fabric is thoroughly impregnated with the salt solution, is thoroughly dried, and is then oxidized or "burnt off" in the same manner as is the ordinary incandescent gas mantle. In this process practically all of the original material of the fabric is removed, leaving a structure of ox-

ide crystals or particles which retains the general form of the original fabric matrix. A large shrinkage occurs in the process, so that a 200 mesh fabric becomes, after burning, an oxide fabric with a mesh of about 500 to the inch. In forming the screen allowance must be made for this shrinkage, the fabric being very slack as originally mounted.

As indicated above, various other oxides and oxide mixtures are possible. The usual gas mantle mixture of thoria and ceria has the disadvantage that it is unstable under bombardment, the thoria being reduced to render the screen inactive. Pure thoria is not subject to this limitation, but is not as sensitive as when sensitized by the uranium oxide.

The various other radiators mentioned, such as lime or calcium oxide, zirconium oxide, etc., will operate, but at greatly less efficiency, as compared with the preferred mixture.

The type of electron gun used is highly efficient, delivering as much as 80 per cent of the total emission of the cathode into the active electron stream, and cathode ray beams carrying as much as 10 milliamperes are readily producible. For television use, the beam is focused by the magnetic field produced by passing direct current through a coil 22, which is coaxial with the beam, so that the entire electron emission of the beam falls upon the screen as a very fine spot or trace.

The beam is systematically deflected by the magnetic field produced by passing an alternating current through the coils 24, so that the beam sweeps across the screen from side to side and falls only instantaneously upon any given elementary area. A similar set of coils arranged at right angles to the coils 24 is also used to deflect the beam in the opposite direction, this additional pair of coils being omitted in the figure for the sake of clarity.

When an alternating current of a different frequency from that passed through the coils 24 is passed through the second set of coils, the trace of the ray will describe a rectangular area upon the screen, traversing each element of the field successively. In practice, an anode potential of 5,000 to 7,000 volts is used, so that from 50 to 70 watts are expended in the beam, and this power is manifested in heating of the screen.

Since the individual fibers of the pile 21 are spaced from the adjacent fibers, the heat generated in the fibers by the impact of the beam is lost almost entirely by radiation, conduction to the adjacent fibers occurring necessarily through the body of the fabric, and being very small due to the low thermal conductivity of the oxide and to its small cross section transverse to the direction of the heat flow.

Since radiation is practically the only channel of heat loss, and since a large amount of power is expended in the extremely small mass of the pile fibers, they are excited to incandescence almost instantaneously. Once excited, they continue to incandesce until the loss of heat by radiation, continuing over a materially greater period than the excitation period, reduces them to darkness.

Using the finest weave velvets as a base, these screens have been satisfactorily operated to display pictures having a detail corresponding to 400 lines, i. e., pictures wherein the area of the focal spot was but $\frac{1}{160,000}$ of the area of the screen. With these pictures transmitted at a rate of twenty per second, the time during which any individual area is bombarded is $\frac{1}{3,200,000}$ of

a second, the excitation occurring twenty times per second. Screens based on coarser fabric are correspondingly slower, but in any case the heating period is extremely short in comparison with the radiating period, so that the heating period may be considered as instantaneous.

If a plain fabric 25, as shown in Fig. 3, be substituted for the pile fabric, the screen becomes too slow for satisfactory television use, although it is still sufficiently rapid for even the most rapid ordinary oscillographic work. Where, as in Fig. 4, a metal foil 26, mounted upon a ring 17, and having its inner space coated with particles of a suitable emitter is used, the heat of the screen is still further reduced, although it may be used for producing oscillographic traces of simple wave forms. The omission of the oxide coating 27 still further reduces the sensitivity of the screen. These forms of the device will therefore not be generally used, owing to the much greater power available in screens of the preferred type, but they are disclosed here primarily to indicate the continuous gradation of characteristics that may be obtained by utilizing the principles here set forth to a greater or less degree.

It will be seen that the success or failure of a screen of the type here described depends on the proper coordination of heat generation and heat dissipation from the incandescent elements of the surface. The effect of a cathode ray beam in heating the anode has long been known, and modern X-ray tubes are customarily operated with their anodes at incandescence. In this case, however, the beam falls constantly on one spot, and the heat generated diffuses quickly throughout the massive target.

In the screen of our invention, however, the beam is constantly moved from one elementary area to another, and the mass of material in the path of the beam at any instant is so small that its rise to incandescence is practically instantaneous. Furthermore, conduction to adjacent elements is so restricted that heat loss by radiation cools the bombarded area before the incandescence can spread appreciably. Were the heat supplied continuously to one spot there would, of course, be spreading of the luminous area no matter how great the thermal resistance. The practically continuous movement of the trace is, therefore, an essential feature in the operation of a screen of this character.

With screens of the pile type, the illumination produced is of the order of 2 candle power per watt of input energy. With 70 watts input the television picture produced on a screen of this type an inch and a half to two inches square, is so brilliant that the screen cannot be viewed directly. It may, however, be projected by a suitable lens system 28, as shown in Fig. 5, upon a projection screen 30 or flat surface having a high coefficient of reflection. Under these circumstances the effect of the illumination pro-

duced is substantially twice to four times that available with home moving-picture outfits using a 100 watt lamp. The actual luminous flux produced is, of course, much less than that of the home projection outfit, but in the case of the screen of our invention it is the image of the luminous source itself which is projected, whereas in the case of the moving-picture film, approximately 90 per cent of the infalling light is absorbed by the film. It is therefore possible, using screens of this type, to project television images in rooms having a fair degree of general illumination, and to a size of from one to five feet square, depending upon the general illumination level and the amount of the power expended in the cathode ray beam.

We claim:

1. Means for producing an incandescent image for projection by a lens system, comprising an envelope containing a thin opaque and planar screen having one surface positioned in the focal plane of said lens system, means for bombarding an opposite surface separated from said first surface by the thinnest section of said screen with a defined cathode ray beam of sufficient intensity to raise both the surface bombarded and the surface presented to said lens to incandescence, and means for moving said beam over said bombarded surface to produce an incandescent image larger than the cross section of said beam.

2. In an image projecting system having an envelope containing a primary light source coaxially positioned between an anode and cathode cooperating to produce a beam of cathode rays, and a lens system, said beam being moved in two dimensions over an image field, said primary light source comprising an opaque screen of incandescible material throughout its thickness and of such thickness that it can be raised to incandescence throughout its thickness and on both its opposite faces by impingement therewith of the beam of rays from said gun, whereby an incandescent image is formed on both sides of said screen.

3. In an image projecting system wherein an optical image is produced within a cathode ray tube and projected onto a viewing screen by an outside lens system, image producing means comprising an envelope containing an anode and cathode cooperating to produce a cathode ray beam of high intensity, a thin opaque screen of incandescible material in the path of said beam and positioned at right angles to the normal undeflected path of said beam, at right angles to the axis of said lens system and between said anode-cathode assembly and said lens, and means for deflecting said beam over successive elementary areas of said screen to produce an incandescent image on both sides thereof.
